BATTER'S PROTECTOR

Ceola F. Doughty, Rte. 1, Old Hammond Highway,
Baton Rouge, La.

Filed Apr. 29, 1959, Ser. No. 809,735

4 Claims. (Cl. 2-2)

This invention relates to sporting equipment and more particularly to a protector for a batter.

An object of the invention is to provide a safety device providing protection for a batter when he is standing at the plate awaiting a pitch from the pitcher on the mound. There are a number of protective devices for athletes and specifically, there are numerous protectors for baseball players. For instance, plastic helmets are used, shin-guards for the catcher, a chest protector for the catcher, a mask also for the catcher, sliding pads and others which are less common. Yet, to date there has been no protection for the batter standing in the batter's box and awaiting a pitch, which protection would be for the chest and lower part of the anatomy. Very serious injury can be caused by a pitch striking a batter in the region of a number of organs including the kidneys and heart. In fact, at least one death has occurred comparatively recently by a pitch striking a youthful baseball player in the region of the heart. The youth died before he could be carried off the baseball diamond.

A protector in accordance with this invention provides protection for either the left or the right side of the batter depending on whether the batter is right-handed or left-handed. A right-handed batter standing in the batter's box, if he is standing properly in accordance with reasonably accepted stances, will have his left arm elevated so that the portion of the arm between the elbow and the shoulder is away from the body, elbow rather high so that this portion of the arm is approximately horizontal. This leaves the under-arm portion of the left side of the right-handed batter exposed and vulnerable to wild and brush-off pitches.

The protector in accordance with this invention is lightweight and covers the above mentioned and described exposed portion of the body of the baseball player when he is standing at the plate. Furthermore, the protector is so constructed that it extends approximately to the vertical center line of the batter and a little farther on both his front and rear sides covering the majority of the stomach area, the kidneys and other organs in the abdominal area.

An important feature of the invention is that it is completely reversible for left-handed and right-handed batters. There is no necessity for a left-handed protector and a right-handed protector inasmuch as both left-handed and right-handed batters may use the protector with equal facility.

These together with other objects and advantages which will become subsequently apparent reside in the details of construction and operation as more fully hereinabove described and claimed, reference being had to the accompanying drawings forming a part hereof, wherein like numerals refer to like parts throughout, and in which:

FIGURE 1 is a perspective view of a batter standing at the plate awaiting a pitch and having one of the protectors as it should be worn.

FIGURE 2 is a front view of the batter in FIGURE 1.

FIGURE 3 is a perspective view of the protector.

FIGURE 4 is a sectional view taken on the line 4-4 of FIGURE 3.

In the accompanying drawings a baseball batter 10 is shown in FIGURE 1 with the bat awaiting a pitch. The batter is a right-handed batter and therefore the protector 12 is arranged to protect the left side of the batter. The protector is constructed of a flexible panel 14 made of a resilient and flexible pad 18, for example sponge rubber,

2

together with two coverings 20 and 22 which may be identical. The coverings are fastened to the front and rear surfaces of pad 18 and are held united thereto preferably by stitching. The stitching 24 may be in a quilted pattern for strength of construction and for neatness of appearance.

The panel may be considered as made of a number of portions in accordance with the positions on the body where they are worn. There is a first portion 26 which covers more than one-half of the chest, abdomen, stomach, etc. (FIGURE 2). This first portion has, when worn, an essentially horizontal lower edge 28, an essentially upright edge 30 connected at right angles to edge 28 and terminating short of the top part of portion 26. Edge 30 continues as an arcuate edge 32 following along portion 26 to the top of the shoulder.

There is an intermediate portion 34 having indefinite boundaries with portions 26 and 36, the portion 36 being identical to portion 26 in construction and size as well as shape. Portion 34, portion 36 and portion 26 have a common lower edge 28. The portion 34 is adapted to fit beneath the under-arm of the batter and extends straight down to cover the vulnerable side of the batter as he stands in the batter's box (FIGURE 1). The upper edge 40 of portion 34 is arcuate and continues upwardly to meet edges 42 and 46 of portions 48 and 50. The arcuate edge 40 forms an armhole through which the left arm of the right-handed batter 10 is passed. The portions 48 and 50 are defined as the upper parts of portions 26 and 36, namely those portions which fit over the front and rear of the shoulder. Edges 42 and 46 are brought together and held in place on the top of the shoulder of the batter by means of straps 52 and 54 having buckles 56 and 58.

There are means, for instance adjustable straps 60 and 62 attached to edges 30 and 31 of portions 26 and 36 respectively. Fasteners, as snaps or hooks and eyes 61 or snaps are on straps 60 and 62 to fasten the ends together. As shown in FIGURE 2 these straps extend around the unprotected side of the batter and are quickly attached and detached to enable the protector to be slipped on and off very rapidly.

By having the protector symmetrical about a line extending from the bottom of the armhole to the center of edge 26, the protector is completely interchangeable by merely reversing it so that it may fit a left-handed batter or a right-handed batter with equal facility.

It is to be understood that various changes may be made herein without departing from the invention. For instance, the straps 52 and 54 may be substituted by other fasteners such as hooks and eyes, snaps or even a less practical slide fastener.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A protector for the chest, stomach, back and one side of a left-handed or right-handed hitting batter, said protector comprising a flexible panel which has a first portion adapted to fit over one side of the chest and stomach area of the batter's body, a second portion adapted to fit over the side of the batter which faces the pitcher, and a third portion adapted to fit over approximately half of the back of the batter, said panel having upper portions formed as integral extensions of said first and third portions and extending upwardly from said first and third portions in front of and in back of the shoulder of the

batter to leave the neck of the batter completely free, means fastening said upper portions together over the same shoulder of the batter adjacent to the side covered by said second portion and thereby leaving an arm hole above said second portion, said panel having an essentially straight lower edge, said arm hole having a curved edge, and said third portion between said lower edge and said arm hole edge being continuous and of approximately the same height as said first portion, said panel being reversible to fit on the left or right side of a batter and the corresponding adjacent left and right parts of his body depending on whether the batter is batting right-handed or left-handed.

2. A protector for the chest, stomach, back and one side of a left-handed or right-handed hitting batter, said protector comprising a flexible panel which has a first portion adapted to fit over one side of the chest and stomach area of the batter's body, a second portion adapted to fit over the side of the batter which faces the pitcher, and a third portion adapted to fit over approximately half of the back of the batter, said panel having upper portions formed as integral extensions of said first and third portions and extending upwardly from said first and third portions in front of and in back of the shoulder of the batter to leave the neck of the batter completely free, means fastening said upper portions together over the same shoulder of the batter adjacent to the side covered by said second portion and thereby leaving an arm hole above said second portion, said panel having an essentially straight lower edge, said arm hole having a curved edge, and said third portion between said lower edge and said arm hole edge being continuous and of approximately the same height as said first portion, said panel being reversible to fit on the left or right side of a matter and the corresponding adjacent left and right parts of his body depending on whether the batter is batting right-handed or left-handed, said panel being constructed of a resilient pad having coverings on both surfaces thereof.

3. A protector for the chest, stomach, back and one side of a left-handed or right-handed hitting batter, said protector comprising a flexible panel which has a first portion adapted to fit over one side of the chest and stomach area of the batter's body, a second portion adapted to fit over the side of the batter which faces the pitcher, and a third portion adapted to fit over approximately half of the back of the batter, said panel having upper portions formed as integral extensions of said first and third portions and extending upwardly from said first and third portions in front of and in back of the shoulder of the batter to leave the neck of the batter completely free,

means fastening said upper portions together over the same shoulder of the batter adjacent to the side covered by said second portion and thereby leaving an arm hole above said second portion, said panel having an essentially straight lower edge, said arm hole having a curved edge, and said third portion between said lower edge and said arm hole edge being continuous and of approximately the same height as said first portion, said panel being reversible to fit on the left or right side of a batter and the corresponding adjacent left and right parts of his body depending on whether the batter is batting right-handed or left-handed, said panel being constructed of a resilient pad having coverings on both surfaces thereof, and means uniting said coverings on said pad.

15 4. A protector for a batter, said protector comprising a flexible panel which has a first portion adapted to fit over one side of the chest and stomach area of the batter's body, a second portion adapted to fit over the side of the batter which faces the pitcher, and a third portion adapted to fit over approximately half of the back of the batter, said panel having upper portions formed as integral extensions of said first and third portions and extending upwardly from said first and third portions in front of and in back of the shoulder of the batter to leave the neck of the batter completely free, means fastening said upper portions together over the same shoulder of the batter adjacent to the side covered by said second portion and thereby leaving an arm hole above said second portion, said panel having an essentially straight lower edge, said arm hole having a curved edge, and said third portion between said lower edge and said arm hole edge being continuous and of approximately the same height as said first portion, said panel being reversible to fit on the left or right side of a batter and the corresponding adjacent left and right parts of his body depending on whether the batter is batting right-handed or left-handed, said first and third portions having outer generally upright edges spaced from each other when said panel is on the body of the batter, and fastening means extending from said edges and engageable around the side of the batter's body opposite to the side covered by said second portion.
